UNITED STATES PATENT OFFICE.

NATHAN SCHWARTZ, OF NEW YORK, N. Y.

RESPIRATOR-MASK.

1,292,095.

Specification of Letters Patent.

Patented Jan. 21, 1919.

Application filed March 28, 1918. Serial No. 225,232.

To all whom it may concern:

Be it known that I, NATHAN SCHWARTZ, a citizen of the United States, and a resident of the city of New York, borough of Manhattan, in the county and State of New York, have invented a new and Improved Respirator-Mask, of which the following is a full, clear, and exact description.

The object of the invention is to provide a new and improved respirator mask more especially designed for the use of persons working in dusty places, and arranged to protect the user against inhaling dust, noxious and poisonous fumes and gases, or infectious and contagious diseases liable to be contracted by inhaling dust containing bacteria of a pathogenic nature. Another object is to permit of conveniently and quickly attaching and holding the respirator mask in position on the face of the user or removing it therefrom whenever it is desired to do so. Another object is to insure a snug fit of the respirator mask to the face of the wearer and without hindering free inhaling and exhaling. Another object is to prevent chafing or otherwise injuring the skin of the wearer.

With these and other objects in view, the invention consists of certain novel features of construction, as hereinafter shown and described and then specifically pointed out in the claims.

A practical embodiment of the invention is represented in the accompanying drawings forming a part of this specification, in which similar characters of reference indicate corresponding parts in all the views.

Figure 1 is a perspective view of the respirator mask as applied;

Fig. 2 is an exaggerated cross section of the same;

Fig. 3 is a rear perspective view of the same; and Fig. 4 is a plan view of a portion of the body before the binding is applied and showing the notch forming a dart.

The body 10 of the respirator mask is formed of a plurality of superimposed pieces 11 of open mesh textile fabrics such as gauze, cheesecloth or similar soft material, the pieces being bound together along the margins by a binding 12 fastened to the pieces 11 by transverse stitches 13. The binding 12 is preferably made of strong close mesh material such as is generally used for binding purposes in garments and the

like to give the desired strength to the body 10 and to prevent distortion of the open mesh pieces 11. The body 10 is approximately straight along the upper edge, and the sides are straight in the upper portion and curved gradually into the approximately semicircular bottom of the body. The binding 12 contains a piece 15 of soft wire or similar pliable material disposed approximately at the middle of the top portion of the body, and this piece of wire is bent so as to conform to the shape of the nose at the bone thereof, it being understood that by bending the wire in this manner the binding and the corresponding adjacent portion of the body is shaped to conform to the shape of the nose, as will be readily understood by reference to Figs. 1 and 3. A similar piece 18 of soft wire or similar pliable material is arranged in the binding at the bottom portion and is bent to conform to the shape of the under side of the chin of the wearer to insure a tight fitting of the bottom edge of the mask under the chin of the wearer.

The sides of the body 10 are provided with ear loops 20, preferably made of elastic bands, each having one end sewed to the corresponding upper corner of the mask at the binding 12, and the other end sewed to the binding a distance down at the corresponding side of the mask. The ear loops 20 are adapted to be passed around the ears of the wearer so as to firmly hold the mask in position on the face of the wearer, it being understood that the ear loops 20 are sufficiently short to require stretching of the same to engage the ears of the wearer to insure a tight holding of the mask on the face of the wearer.

In order to prevent dust from passing the binding at the upper edge of the mask, use is made of a retaining flap 25 of a doubled-up textile fabric such as is used for the binding 12, and this retaining flap is arranged on the inner side of the body 10 and is secured by stitches 26 to the body 10 adjacent but spaced from the inner edge of the binding 12 so that the retaining flap 25 extends upwardly onto the corresponding top portion of the binding 12. A similar retaining flap 27 is arranged on the inner side of the body at the bottom and side portions adjacent the corresponding portion of the binding 12, and this retaining flap 27 is fastened to the

body 11 by stitches 28 and extends onto the binding, as plainly indicated in Figs. 2 and 3.

It will be noticed that by the arrangement described, the user of the mask can readily shape the nose and chin portions thereof to correspond to the configuration of the nose and chin of the wearer with a view to insure a tight fitting of the mask on the face of the wearer at the time the loops 20 are engaged with the ears. It will also be noticed that by having the binding a tight joint is had between the skin of the face and the binding while the body 10 is practically out of contact with the skin and sufficient space is provided for the mouth and nostrils to insure free inhaling and exhaling.

In practice, the middle, top and bottom portions of the body 10 are provided with darts 30 and 31 to give the proper shape to the body 10 for the nose and chin. By the arrangement described the mask assumes the shape of a bowl or cup and thus provides a breathing chamber which permits indirect respiration.

By shaping the body 10 as described and shown in the drawings, the undesirable and unsightly muzzle appearance is avoided and the respirator appears with a veil effect or a mask effect.

It will be noticed that by superimposing a number of pieces 11 of open mesh textile fabrics the user can breathe freely, and the air drawn through the meshes on inhaling is thoroughly filtered and purified, and hence only pure air enters the user's system. It will further be noticed that the meshes of

succeeding pieces 11 are naturally staggered whereby dust and other solid and finely divided matter is retained. The respirator 40 mask can be washed from time to time to wash out the solid matter and thus permit the use of the mask for a long time.

The respirator mask shown and described is simple in construction and can be cheaply 45 manufactured and readily applied by the user.

Having thus described my invention, I claim as new and desire to secure by Letters Patent:—

1. A respirator mask having a body formed of a plurality of superimposed pieces of open mesh textile fabrics, a binding for holding the pieces together, and retaining flaps secured to the inner side of the body 55 adjacent the binding and overlapping the latter in an outward direction.

2. A respirator mask having a body portion formed of a plurality of superimposed pieces of textile fabric, said body portion 60 being provided with a transverse dart arranged near and beneath the upper edge thereof to impart to the mask a desired fullness for the reception of the nose, a binding at the edges of said pieces to hold them together, a piece of soft wire secured to the body portion at the upper edge thereof and adapted to be bent into a shape for the reception of the nose, a retaining flap secured to the inner side of the body portion near its 65 upper edge and partly overlapping the binding, and retaining elements secured to the sides of the body portion.

NATHAN SCHWARTZ.
